ENGINE

Hugh E. Hogan, Owego, N. Y.

Application December 5, 1939, Serial No. 307,703

9 Claims. (Cl. 123—50)

My invention relates to engines, and has among its objects and advantages the provision of a multicylinder engine so designed as to utilize a single crank and connecting rod.

5 In the accompanying drawings:

Fig. 1 is a side elevational view of an engine embodying my invention;

Fig. 2 is a top plan view with certain parts broken away for the sake of clearness;

10 Fig. 3 is a longitudinal sectional view;

Fig. 4 is a sectional view along the line 4—4 of Fig. 3;

Fig. 5 is a sectional view along the line 5—5 of Fig. 3;

15 Figs. 6, 7, 8 and 9 are diagrammatic views illustrating the operation of the multicylinder feature with respect to a single crank;

Fig. 10 is a sectional view of an engine having a lesser number of cylinders and arranged vertically; and

Fig. 11 is a sectional view similar to Fig. 10 but rotated ninety degrees.

In the embodiment selected to illustrate my invention, the engine includes a base structure

25 10, see Figs. 1 and 3, which base structure includes pedestals 12 provided with bearings 14

which support the crankshaft 16 having a single crank 18. To the wall 20 of the base 10 I connect a cylinder unit 22, which unit is illustrated

30 as lying horizontally. In an engine embodying a large number of cylinders, particularly of the

horizontal type, it may be necessary to provide a support 24 for the engine at its end opposite the base 10, as indicated generally in Figs. 1

35 and 3.

Cylinder unit 22 comprises a stationary half 26 and a slidable half 28, which slidable half is connected at 30 with a connecting rod 32 connected with the crank 18 in the usual manner.

40 Thus, the half 28 is slidably related to the half 26 and motion is imparted to the crank 16 through the reciprocatory motion of the half 28 relatively to its companion half 26.

Half 26 comprises sections 34, 36 and 38 ar-

45 ranged in end to end relation and connected into a unitary structure through the medium of bolts 40 associated with the flanges 42. Section 34

has one end bolted to a neck 44 fashioned as an

integral part of the wall 20. Similarly, half 28

50 includes a section 46 and a section 48 each hav-

ing a flange 50 fixedly connected with the other

flange by bolts 52. Sections 26 and 28 are semi-

circular in cross section and arranged to pro-

vide a bore 54 of uniform diameter, see Fig. 4.

55 Fig. 3 illustrates the half 26 as being somewhat

longer than the half 28 to accommodate the sliding motion of the half 28.

Pistons 56 and 58 are fixedly secured to the half 26, and pistons 60, 62 and 64 are also fixedly connected with the half 28. The pistons 56 and 58 have 180° of their peripheral faces slidably engaging the bore face of the half 28, while the pistons 60, 62 and 64 have 180° of their peripheral faces slidably engaging the bore face of the half 26. While the half 28 slides longitudinally of the half 26, the end pistons 60 and 64 of the half 28 slidably engage the half 26 so as to provide a closed combustion chamber, with the half 26 of such length as to maintain a closed combustion chamber in all relative positions of the half 28.

Piston 56 is provided with a flange 66 positioned between the adjacent flanges 42 of the sections 34 and 36 and clamped therebetween by the bolts 40. Fig. 3 illustrates the pistons 56 and 58 in elevation. In the same way, piston 58 is provided with a flange 68 secured between the adjacent flanges 42 of the sections 36 and 38. Piston 60 also includes a flange 70 secured between the flange 72 on the section 46 and a flange 74 on a collar 76. Flanges 70, 72 and 74 are fixedly secured by bolts 78. Piston 60 includes projections 80 between which one end of the connecting rod 32 is positioned and pivotally connected thereto by a wrist pin 82, see Fig. 2.

Flange 84 of the piston 62 is secured between the adjacent flanges on the sections 46 and 48, while the flange 86 on the piston 64 is positioned between a flange 88 on the section 48 and a flange 90 on a collar 92. Flanges 86, 88 and 90 are secured into a unitary structure by bolts 94.

Sections 34, 36 and 38 of the half 26 are provided with longitudinal flanges 96 which have faces 98 lying in a common plane. The faces 98 upon the two sides of the half 26 are arranged 180° apart, see Figs. 3, 4 and 5. Sections 46 and 48 are also provided with flanges 100 having faces 102 lying in common planes and lying upon the faces 98. Flanges 100 are somewhat narrower than the flanges 96 and have faces 104 against which I position aligning guides 106. Aligning guides 106 lie on the areas of the faces 98 extending beyond the faces 104, and each aligning guide 106 upon each side of the half 28 extends the full length of the latter, as illustrated in Fig. 1.

Aligning guides 106 are made secure to the flanges 96 by bolts 108 passing through openings 110 in the guides and threaded into the flanges 96, with the heads 112 of the bolts countersunk

55

into the guides, as illustrated in Figs. 1, 4 and 5. Openings 110 are somewhat larger than the diameter of the bolts 108 so that the aligning guides 106 may be adjusted to the faces 104.

6. Referring to Figs. 4 and 5, the flanges 100 are provided with angular faces 114 for engagement with the angular faces 116 on bars 118 lying on the aligning guides 106, with the bars 118 made secure by bolts 120 which extend through openings 122 in the bars and openings 124 in the aligning guides 106 and threaded into the flanges 96, see Fig. 1. Openings 124 are of larger diameter than the bolts 120 to permit the aligning guides 106 to be adjusted. Bars 118 are coextensive in length with the aligning guides 106, see Fig. 1.

Each of the pistons 56, 58, 60, 62 and 64 is provided with a plurality of rings 126 which extend completely about their respective pistons in the usual manner. In Fig. 3, I illustrate the half 26 as being provided with intake ports 128, 130, 132 and 134. Half 26 is also provided with a series of exhaust ports 136, 138, 140 and 144 respectively associated with the intake ports 128 to 134. Figs. 1, 2 and 3 illustrate the pistons 60, 62 and 64 in one extreme position, and in the other extreme position, the pistons will take the positions indicated at 146, 148 and 150, see Fig. 3. According to Fig. 3, the pistons 60 and 62 are separated from the pistons 56 and 58 by spaces 152 and 154, respectively, when in one extreme position, which spaces are such as to maintain the intake ports 128 and 130 as well as the exhaust ports 136 and 140 uncovered at all times. In the other extreme position of the pistons 60, 62 and 64, the piston 62 is separated from the piston 58 by a space 156, and the piston 64 is separated from the piston 58 by a space 158, which spaces are identical with those illustrated at 152 and 154. 40 All the intake ports and exhaust ports will, of course, be provided with conventional chambers and intake and exhaust valves in the manner of conventional internal combustion engines. Such valve devices are old and well known in the art and need not be described in detail.

Referring to Fig. 2, piston 60 is provided with two compression locks 160 which are in the nature of rectangular blocks arranged to slide on the faces 98, as illustrated in Figs. 4 and 5. 50 Compression locks 160 are recessed at 162 to partly receive the sealing rings 126 so that the locks will slide with the pistons. Each of the pistons 56, 58, 60, 62 and 64 is provided with two compression locks 160. These blocks are identical in construction and operation so that the description of one unit will apply to all. Referring to Fig. 5, the half 28 is recessed at 164 to house the locks 160, which locks have lengths corresponding to the lengths of their respective pistons, with the outer edges of the locks associated with the half 28 arranged in sliding engagement with the aligning guides 106. In Fig. 5, the locks 160 are urged against the faces 98 by reason of springs 166 lying in recesses 168 in the half 28. 60 Fig. 4 illustrates the compression locks 160 associated with the piston 56 as lying in recesses 170 in the half 26, and urged against the faces 102 by springs 172 disposed in recesses 174 in the half 26.

70 From the foregoing description of the various parts of the device, the operation thereof will be readily understood. Referring to Fig. 6, the half 28 may be considered as being in a firing position, at which time an explosion takes place 75 in the space or chamber 152. As the half 28

is driven in the direction of the arrow 176, fuel in the space or chamber 156 will be compressed and fuel will be sucked into the space or chamber 154. At the same time, space or chamber 158 will exhaust. Fig. 7 illustrates the half 28 5 positioned for its return stroke, at which time chamber 152 will exhaust and an explosion takes place in chamber 156. Fuel will be compressed in the chamber 154 and chamber 158 will suck in a new charge. Thus, the engine delivers one 10 explosion for each half turn of the crank 18.

With the half 28 again positioned as illustrated in Fig. 8, an explosion takes place in chamber 154 while chamber 156 will exhaust and chamber 152 will draw in a new charge. Chamber 158 15 will compress the fuel therein. With the half 28 moved to the position of Fig. 9, an explosion takes place in chamber 158 and chamber 154 will exhaust. Chamber 156 will take in a new charge and chamber 152 will compress the charge 20 therein.

It will thus be seen that I have provided an engine which may be of the multicylinder type with respect to function, and in which the multiple cylinders are so devised as to actuate a 25 single crank. The engine is characterized by relatively light weight and is so constructed as to minimize friction, as well as to embody relatively few parts. The shape of the engine is such as to minimize air resistance when used 30 as an airplane motor. Some of the cylinders might be employed for air compressing purposes so that the engine and air compressor would be directly associated with the single crank. While the cylinder unit 22 embodies a split formation 35 represented by the halves 26 and 28, the two halves are effectively joined for sealing purposes by reason of the ground surfaces 114 and 116. The compression locks 160 associated with all the pistons performs a sealing function so as to 40 hold the gases from passing out the ends and between each cylinder. Pressure inside the cylinder unit merely tends to additionally seal the two halves, and the aligning guides 106 also perform a sealing function. 45

In Figs. 10 and 11, I illustrate a similar engine with the exception that the cylinder unit 178 includes one fixed piston 180 and two movable pistons 182, with the cylinder unit 178 arranged vertically. The cylinder unit is completely enclosed by reason of a housing 184, which housing may be controlled for temperature through the medium of a suitable refrigerating system (not shown). Cylinder unit 178 is mounted on a crank case 186, and the crank 188 and the connecting rod 190 are conventional. Figs. 1 to 9, inclusive, illustrate an engine embodying a four cylinder design, while the engine of Figs. 10 and 11 embodies a two cylinder construction. 50

Having thus described certain embodiments of my invention in detail, it is, of course, understood that I do not desire to limit the scope thereof to the exact details set forth except insofar as those details may be defined in the appended claims. 60

I claim:

1. An engine comprising a crank, a cylinder unit comprising a relatively fixed part and a relatively movable part, said relatively fixed part and said relatively movable part being so fastened as to provide a bore, an operating connection between said movable part and said crank, said relatively fixed part comprising sections, first pistons disposed in said bore, and means for fixedly connecting said sections and said first 70 75 75

5 pistons into a unitary structure, said second part comprising sections, second pistons disposed in said bore, and means for fixedly connecting said last-named sections and said second pistons into a unitary structure, said first and second pistons being so arranged as to provide a plurality of firing chambers.

2. An engine comprising a crank, a cylinder unit comprising a relatively fixed part and a relatively movable part, said relatively fixed part and said relatively movable part being so fashioned as to provide a bore, an operating connection between said movable part and said crank, first pistons fixedly connected with the stationary part and disposed in said bore, second pistons fixedly connected with said movable part and disposed in said bore, said first and second pistons being so arranged as to provide a plurality of firing chambers, compression locks operatively connected with said first pistons and said second part for sliding engagement with said second part, and compression locks operatively connected with said second pistons and said second part and arranged for sliding engagement with said first part.

25 said first part.

30 3. An engine comprising a crank, a cylinder unit comprising a relatively fixed part and a relatively movable part, said relatively fixed part and said relatively movable part being so fash-
35 ioned as to provide a bore, an operating connec-
tion between said movable part and said crank, first piston means fixedly connected with the stationary part and disposed in said bore, sec-
40 ond piston means fixedly connected with said movable part and disposed in said bore, said first and second piston means being so arranged and cooperating in such manner as to provide a plu-
45 rality of firing chambers, compression locks op-
eratively connected with said first piston means and said second part for sliding engagement
50 with said second part, and compression locks op-
eratively connected with said second piston means and said second part and arranged for sliding engagement with said first part.

45 4. An engine comprising a crank, a cylinder unit comprising a relatively fixed part and a relatively movable part, said relatively fixed part and said relatively movable part being so fashioned as to provide a bore, an operating connection between said movable part and said crank, a piston fixedly connected with said stationary part and disposed in said bore, second pistons fixedly connected with said movable part and disposed in said bore, said first piston and said 50 second pistons being so arranged and cooperating in such manner as to provide a plurality of firing chambers, compression locks operatively connected with said first piston and said second part for sliding engagement with said second part, and compression locks operatively connected with said second pistons and said second part and arranged for sliding engagement with said first part.

55

60

5. An engine comprising a crank, a cylinder unit comprising a relatively fixed part and a relatively movable part, said relatively fixed part and said relatively movable part being so fashioned as to provide a bore, an operating connection between said movable part and said crank, said relatively fixed part comprising sections, first pistons disposed in said bore, means for fixedly connecting said sections and said first pistons into a unitary structure, said second part comprising sections, second pistons disposed

in said bore, means for fixedly connecting said last-named sections and said second pistons into a unitary structure, said first and second pistons being so arranged as to provide a plurality of firing chambers, compression locks operatively connected with said first pistons and said second part for sliding engagement with said second part, and compression locks operatively connected with said second pistons and said second part and arranged for sliding engagement with 10 said first part.

6. An engine comprising a crank, a cylinder unit comprising a relatively fixed part and a relatively movable part, said relatively fixed part and said relatively movable part being so fashioned as to provide a bore, an operating connection between said movable part and said crank, first pistons fixedly connected with the stationary part and disposed in said bore, second pistons fixedly connected with said movable part and disposed in said bore, said first and second pistons being so arranged as to provide a plurality of firing chambers, and sealing means for slidably guiding the relatively movable part with respect to the relatively fixed part. 25

7. An engine comprising a crank, a cylinder unit comprising a relatively fixed part and a relatively movable part, said relatively fixed part and said relatively movable part being so fashioned as to provide a bore, an operating connection 30 between said movable part and said crank, first piston means fixedly connected with the stationary part and disposed in said bore, second piston means fixedly connected with said movable part and disposed in said bore, said first and 35 second piston means being so arranged and cooperating in such manner as to provide a plurality of firing chambers, and sealing means for slidably guiding the relatively movable part with respect to the relatively fixed part. 40

8. An engine comprising a crank, a cylinder unit comprising a relatively fixed part and a relatively movable part, said relatively fixed part and said relatively movable part being so fashioned as to provide a bore, an operating connection between said movable part and said crank, a piston fixedly connected with said stationary part and disposed in said bore, second pistons fixedly connected with said movable part and disposed in said bore, said first piston and said second pistons being so arranged and cooperating in such manner as to provide a plurality of firing chambers, and sealing means for slidably guiding the relatively movable part with respect to the relatively fixed part. 45 50 55

9. An engine comprising a crank, a cylinder unit comprising a relatively fixed part and a relatively movable part, said relatively fixed part and said relatively movable part being so fashioned as to provide a bore, an operating connection between said movable part and said crank, said relatively fixed part comprising sections, first pistons disposed in said bore, means for fixedly connecting said sections and said first pistons into a unitary structure, said second part comprising sections, second pistons disposed in said bore, means for fixedly connecting said last-named sections and said second pistons into a unitary structure, said first and second pistons being so arranged as to provide a plurality of firing chambers, and sealing means for slidably guiding the relatively movable part with respect to the relatively fixed part. 60 65 70

HUGH E. HOGAN.
